FLETCHING JIG

Edward C. Schoor, 1022 4th Ave. N., Moorhead, Minn.
Filed Nov. 27, 1959, Ser. No. 855,925
3 Claims. (Cl. 269—38)

This invention relates generally to archery equipment and more particularly to a novel device for fletching arrows in which the arrow shaft is held in a manner which will allow the vanes of an arrow to be attached to the shaft in their exact proper location.

For many years the accepted number of feathers or vanes which were fletched to an arrow had been limited to three which were spaced at 120° intervals. However, recent experiment has proved that the use of more and smaller vanes on an arrow offers less resistance, hence more speed and a flatter flight trajectory, and hence better shooting accuracy. Therefore, vanes are now frequently used which are shorter, lower and from 3 to 8 in number. A few fletching jigs have been devised for simultaneously applying three vanes to the shaft, but the professional or expert arrow maker has usually preferred the single vane fletching device due to the generally inferior quality of the fletchings of multiple vane jigs. In view of the above, an object of my invention is the provision of a novel fletching jig which will apply a high quality fletch of from 3 to 8 vanes on an arrow shaft in one set-up, and will also fletch the vanes with any desirable degree of angle or spiral with respect to the shaft of an arrow.

A further object of my invention is the provision of a fletching jig which will apply the vanes quickly and easily, and yet will do so with an extremely high degree of accuracy.

A still further object of my invention is the provision of a fletching jig, which, in addition to fletching all of the vanes of an arrow in one set-up, is extremely useful in its ability to replace one broken vane of an arrow without disturbing the other good ones. Further, this feature is not hindered by the presence of a broadhead on the arrow, since the structure of my novel jig facilitates the insertion of a broadheaded arrow without disturbing any of the remaining vanes.

Another object of my invention is the provision of a fletching jig which has a nock holder which is readily and accurately adjustable so as to position the index of the nock holder in alignment with the cock feather or a position corresponding therewith.

A further object of my invention is the provision of a fletching jig which is simple to use, durable in construction, and which may be economically manufactured.

The above and still further objects of my invention will become apparent from the following detailed specification, appended claims and attached drawings.

Referring to the drawings wherein like characters indicate like parts throughout the several views:

FIG. 1 is an elevational view of my complete fletching jig with an arrow shaft inserted therein and the vane clamps positioned thereon, some parts broken away and some parts shown in section;

FIG. 2 is a view in top plan;

FIG. 3 is a view in bottom plan;

FIG. 4 is a view in horizontal section taken on the line 4—4 of FIG. 1, the vane clamps being omitted;

FIG. 5 is a view in horizontal section taken on the line 5—5 of FIG. 1, the vane clamps being omitted;

FIG. 6 is a view in vertical section taken generally on the line 6—6 of FIG. 2;

FIG. 7 is a view in horizontal section taken on the line 7—7 of FIG. 1;

FIG. 8 is a fragmentary sectional view taken on the line 8—8 of FIG. 5; and

2

FIGS. 9—13 are diagrammatic views of the different fletching positions attainable with my novel fletching jig.

Referring with greater particularity to the drawings, the reference letter A represents generally the shaft of an arrow, and the letter B represents the nock of an arrow, which is the portion secured to the rear end of an arrow for positioning the arrow on the bowstring. The reference letter C represents generally the fletching or cumulatively, the feather vanes of an arrow as shown particularly in FIG. 7, which of course, are also sometimes fabricated from plastic and rubber. The reference letter D represents a bowstring, as shown by broken lines in FIGS. 9—13.

The reference numeral 1 represents generally the main structure of my fletching jig, and is comprised of a pair of indexing heads represented generally by the numerals 2 and 3, respectively, and maintained in fixed relation with one another by a plurality of rods 4. The heads 2, 3, are axially associated with the axis of an arrow shaft, 5 and may be easily fabricated so as to be annular in transverse section. The indexing head 2 is preferably, and as shown, axially formed to define a base for standing the jig 1 on a horizontal surface whereby the other head 3 is positioned vertically above the base head 2. The head 2 has a nock holder, represented generally by the numeral 5, axially seated therein for rotatable adjustment with respect to the heads 2, 3. The nock holder 5 may be of any conventional structure, but it preferably and as shown comprises a generally cylindrical bushing 6 having a nock rod 7 seated generally transversely therein. The bottom of the head 2 has a plurality of indicia 8 circumferentially spaced about said bushing 6 and cooperating with a single mark 9 on said bushing 6 for the purpose of properly aligning the index rib b' of the nock B of an arrow to be fletched with the vanes C to be placed thereon. The index rib b', which is integrally molded on most nocks B, serves the purpose of helping the archer to quickly nock the arrow on the bow, not shown, in a position which will allow the arrow fletching C to pass by the bow with as little resistance as possible when the arrow is released. For this purpose, the arrow is always nocked with the index rib b' in a position normal to the bowstring D, as shown in FIGS. 9—13. Therefore, when the arrow is fletched, the index rib b' must be accordingly placed in the proper position, which in the case of a three vane fletch, as shown in FIG. 9, will be in alignment with the cock feather, which is the feather normal to the bowstring D, as above explained. This is easily accomplished by aligning the mark 9 with the indicia 8a. Of course, when more than three vanes are used in fletching an arrow, as shown in FIGS. 10—13, the index rib b' must also be accordingly aligned in the proper position, which in the four vane fletch of FIG. 10 is easily obtained by simply aligning the mark 9 with the indicia 8b. Where the alternate four vane fletch of FIG. 11 is desired, the mark 9 is then aligned with the indicia 8c. When the six, FIG. 12, and eight, FIG. 13, vane fletches are used, the circumferential closeness of the vanes tends to reduce the advantages gained by proper location of the index rib b'. However, since the vanes are radially shorter, the drag caused by their passing over the bow, not shown, in a position nearly normal thereto is not appreciably greater. In this respect the least resistance is obtained with the six vane fletch of FIG. 12 by aligning the mark 9 with the indicia 8d, and similarly aligning the mark 9 with the indicia 8e when the eight vane fletch of FIG. 13 is desired. With the use of the indicia 8 and the mark 9, proper alignment of the index rib b' is automatically assured, and is quick and easy to obtain. For the purpose of releasably maintaining the nock holder 5 properly aligned after adjusted, the

set screw 16 and threaded radial aperture 11, are provided.

The upper indexing head 3 has a fixed outer body portion 12 which has a circular aperture 13 co-axial therewith. Co-axially disposed within said outer body portion 12, and rotatably adjustable therewith, is an annular inner body portion 14 having a co-axial circular aperture 15 therein for receiving the shaft A of an arrow. The set screw 16 and threaded radial aperture 17 are provided for releasably securing the inner body portion 14 after rotatable adjustments. In order to securely center an arrow shaft A within the annular inner body portion 14 of the head 3, a centering plate 18 is adjustably secured to the upper side 19 of said inner body portion 14. The centering plate 18 is generally semi-circular and has a generally axially cut V-shaped notch 19' spaced intermediate its diametric edge 20. The arcuately formed sides 21, 22 of both the centering plate 18 and the inner body portion are adjustably held in communication with each other by a pair of circumferentially spaced tabs 23 on said centering plate fastened by a pair of corresponding screws 24. The aperture 15 defined by the inner body portion 14 should be of a diameter large enough to permit passage of broadheaded arrows therethrough, and also for this purpose, the centering plate 18 has a suitably located slot 25 extending generally radially outward from said notch 19' to permit the passage of the blades of broadheaded arrows, not shown. This important feature will be operatively explained hereafter. So that an arrow shaft A may be accurately and properly centered and releasably secured within said notch 19' of said centering plate 18, a post 26 is mounted on said outer body portion 12 and has an elongated spring 27 depending laterally therefrom to biasingly engage the shaft against said notch 19'.

The bottom of the inner body portion 14 of the upper head 3 and the top of the lower head 2 have circumferentially spaced and radially disposed guide slots 28 opposingly alignable respectively with each other. These slots 28 are spaced so as to facilitate the fletching patterns shown in FIGS. 9-13. Vertically disposed between said heads 2, 3 and radially movable toward and away from an arrow shaft A within said slots 28 for radial displacement from said indexing heads 2, 3, are a plurality of elongated vane clamps each represented generally by the numeral 29. Each of said vane clamps 29 comprises a pair of hingedly connected and generally flat clamping plates 30, 31, together with means represented generally by numeral 36, for biasing the plates 30, 31 in generally flat engagement with one another. The clamping plates 30, 31 are hingedly connected near their radially outward edges 32, 33 preferably, and as shown, by a pair of spherical bearings 34 seated in longitudinally spaced and cooperating apertures 35 in each of said clamping plates 30, 31 in association with said biasing means 36. Said biasing means 36 preferably comprises a pair of U-shaped spring clamps 37, the radially inward edges 38, of which engage said plates 30, 31 radially inwardly of said bearings 34. The radially outward edges 32, 33 of said clamping plates 30, 31 depend slightly oppositely outwardly to form handles 40 for the easier application of pressure to thereby open and close the vane clamps 29. One of said clamping plates 30 is of a slightly greater longitudinal length than its cooperating plate 31, and the extensions 41 formed thereby communicate with the slots 28.

For the purpose of imparting revolution to an arrow, it is sometimes desired to fletch the vanes C to the arrow shaft A at an angle to the shaft, the front end of each vane being centered and the rear of the vane angling in a straight line therefrom. Such a fletching may be easily and quickly accomplished by my invention merely by loosening the set screw 16 and slightly rotating the inner body portion 14 within the outer body portion 12 of the upper head 3, and then tightening the set screw 16 again. It will be obvious that either a left wing fletch or a right

wing fletch may be easily applied by rotating said inner body portion 14 in the desired direction.

Having described my invention in detail, the simple operative techniques incident to efficient use of my invention will be outlined. After inserting the arrow shaft A through both heads 2, 3, and thereafter placing the nock B in the nock holder 5, the holder 5 is adjusted and set as earlier explained. Then the required number of vanes C are secured one each within the clamps 29 with only their quill portions c' showing. Since the vanes C are trimmed with their quill portions c' extending outward from one side only of the plane of the vanes, they are placed between the vane clamps 30, 31 with the quill portions c' extending toward the longer clamping plate 30 in the case of a right wing fletch, as shown in FIG. 7, and oppositely so with a left wing fletch. This arrangement maintains the vanes C in generally perpendicular relationship to the surface of the arrow shaft A. If only three vanes are to be applied, they are patterned as shown in FIG. 9, but if four vanes are to be applied, then either of the patterns of FIGS. 10 or 11 are used. If six vanes are to be applied, three are first applied in the regular pattern, and then three more are later applied and spaced therebetween. The same repeating procedure of four following four all at even spacing is used when eight vanes are to be applied. When the desired pattern has been chosen, and the angle set as explained above (if desired), glue is applied to the exposed quill portions c' of the vanes C and the clamps 29 are then inserted in the plate slots 28 corresponding with the selected pattern (FIGS. 9-13). Then adequate means, such as rubber bands 42, for biasing the clamps 29 against the shaft A of an arrow, are applied to the jig 1. After the glue has dried, the arrow is removed and the vanes C are suitably trimmed.

If, as often is the case, it is desired to replace a single broken vane from an arrow without removing the good vanes, and the arrow is also of the broadhead type, this operation may also be easily accomplished by my invention without removing the broadhead. The broadheaded arrow is inserted angularly upwardly from the side of the jig and from the bottom of the upper head 3 with one of the blades of the head passing through the slot 25 of the centering plate 18. The shaft A is then pulled continuously upward until the nock B may be seated down into the nock holder 5. Then the repair may be made as explained above by using the required number of vane clamps 29.

This invention has been thoroughly tested and found to be completely satisfactory for the accomplishment of the above objects; and while I have shown a preferred embodiment thereof, I wish it to be specifically understood that same may be modified without departure from the scope and spirit of the appended claims.

What I claim is:

1. In a fletching jig for fletching up to a maximum of eight arrow vanes in one set-up; a pair of axially spaced indexing heads mounted in a fixed relationship with one another; one of said heads comprising a nock holder axially seated therein for rotatable adjustment with respect thereto and the other said head, and means for releasably securing said nock holder in any selected angular position; the other of said heads comprising a fixed outer body portion having a circular aperture co-axial therewith, a co-axially disposed rotatably adjustable annular inner body portion seated within said outer body portion and adapted to receive the shaft of an arrow, means for releasably securing said inner body portion in any selected angular position, a centering plate adjustably secured to the axially outer side of said annular inner body portion for centering an arrow shaft therein, said centering plate defining at its generally radially inwardly disposed edge a centrally located generally V-shaped notch, and means for releasably retaining the shaft of an arrow in engagement with the generally V-shaped notch of said centering plate; and a plurality, at least three and at most eight, of elongated

vane clamps for use between said spaced indexing heads; said indexing heads each further defining a plurality, at least three and at most eight, of circumferentially spaced and radially disposed guide slots opposing the other indexing head and aligned therewith; the opposing guide slots of the spaced indexing heads slidably receiving opposite end portions of different vane clamps to maintain said clamps in circumferentially spaced radially disposed relationship with freedom for radial movements toward and away from an arrow shaft and for radial displacement 10 from the indexing heads.

2. The structure defined in claim 1 in which said centering plate of said other indexing head also defines an elongated slot which extends generally radially outwardly from the apex of said generally V-shaped notch for allow- 15

ing the passage of the blades of broad-head arrows there-through.

3. The structure defined in claim 2 in which said means for releasably retaining the shaft of an arrow comprises leaf spring means secured to said outer body portion of said other indexing head.
